APPLYING MACHINE

William C. Card, Jr., Winthrop, Mass., assignor
to Compo Shoe Machinery Corporation, New
York, N. Y., a corporation of Delaware

Application January 4, 1934, Serial No. 705,180

10 Claims. (Cl. 91—50)

This invention relates to a functionally and structurally improved applying machine. While a machine constructed in accordance with the teachings of the present invention is capable of use in numerous different associations, it is intended to be employed in applying cement or adhesive, and according to a more specific aspect of the invention it is a primary object to provide a cement applying machine intended for use in the manufacture of shoes and similar articles.

A further object of the invention is that of constructing a cement applying machine in which the application of cement may be controlled with that degree of nicety which is requisite to work of uniform quality, and to satisfactory mass production.

A further object of the invention is that of providing a machine of this character which may readily be manipulated and adjusted by the operator to conform to his own physical characteristics, and also to that of the work which is being performed.

A still further object is that of constructing an applying machine in which the parts are readily accessible for the purpose of cleaning, inspection, and adjustment.

An additional object is that of furnishing an apparatus of this character, the parts of which will be relatively few in number and individually rugged in construction, these parts being capable of ready assemblage, to provide a unitary apparatus operating over long periods of time with freedom from mechanical difficulty.

With these and other objects in mind, reference is had to the attached sheets of drawings illustrating one preferred embodiment of the invention, and in which—

Fig. 1 is a fragmentary sectional side view of the upper portion of the applying machine, and taken along the lines 1—1 and in the direction of the arrows as indicated in Fig. 2;

Fig. 2 is a partly sectional end view thereof;

Fig. 3 is a sectional view taken along the lines 3—3 and in the direction of the arrows as indicated in Fig. 1; and

Fig. 4 is a fragmentary view of a type of base which may form a part of the machine.

As afore brought out, there is provided, by means of the present invention, an applying machine capable of use in numerous different associations, but which is primarily intended in connection with the manufacture of shoes and similar products. Accordingly, in the following description and in the annexed drawings the in-

vention has been illustrated in this preferred embodiment. This, however, is not to be taken in other than an illustrative sense except where restriction is indicated in the appended claims.

Thus, referring primarily to Fig. 4, it will be seen that the numeral 5 indicates a base upon which a motor 6 is preferably mounted. Positioned to one side of this motor, and conveniently integral with the base, an abutment 7 is provided. The machine proper terminates in the 10 portion 8 straddling this abutment and is maintained in pivotal association therewith by means of a bolt 9. The motor has its power shaft enclosed in a housing 10, which is extended, as at 11, to accommodate a worm and worm wheel 15 (not shown), the latter driving a shaft 12. This shaft is axially aligned with the bolt or pin 9, so that a swinging of the machine proper will in no wise affect or necessitate a rearrangement of the motor drive hereinafter described.

As afore brought out, the portion 8 serves merely as a mounting for the machine proper, and the latter includes a casing 13 providing a reservoir or container with which a cover 14 is detachably associated by, for example, bolts 15. 25 Pivotally secured to the cover, as at 16, is an encasing or housing element 17, the latter being normally maintained against displacement from closed position as, for example, by bolts 18, which engage with screw threaded bores provided in 30 abutments 19 forming a part of the main casting or body.

Disposed within the casing 13 is a body of liquid cement or other similar material, as indicated at 20, and partially immersed therein is a primary cement wheel 21, mounted upon a rotatably supported shaft 22. The casing 13 may be formed with a depressed portion 23, providing a sediment trough, and a plug 24 may be positioned at this point so that the reservoir 40 may be drained and cleaned. A shield 25 may be provided, and this element is mounted to extend in a substantially horizontal plane and above the body of fluid 20. The shield is formed with an opening or slot through which the upper 45 portion of the wheel 21 extends, and a wiping element 26 may be mounted upon this shield to lie in proximity to the periphery and adjacent surfaces of the wheel 21. This wiping element is preferably formed of fibre, and may be adjustable towards and away from the wheel by having its body formed with a slot through which a thumb-screw 27 extends. The latter will, of course, be normally tightened so that the wiping element will be rigid with the shield, and 55

a spring 28 may also be provided to lie against the upper surface of the wiping element to prevent displacement of the latter.

Disposed above the primary wheel 21 is a secondary wheel 29, the latter being mounted upon a rotatably supported shaft 30, the distance between this shaft and the shaft 22 being such that the peripheries of the wheels clear one another by approximately one thirty-second of an inch. This spacing may, of course, be varied according to the viscosity of the fluid which is employed, as well as the character of work which is being undertaken, but in any event it will be appreciated that by this construction a certain amount of fluid adheres to the adjacent surface of wheel 21 and is transferred from the latter to the periphery of wheel 29.

Adjacent its forward edge the casing 13 may be thickened, to provide a sleeve portion 31, to rotatably enclose a shaft 32. At the upper end of this sleeve portion there is positioned a cement brush, preferably including a body 33 of rubber or similar material, which is disposed upon a flanged disk 34 and retained in position thereon by a clamping plate 35. The shaft 32 is preferably supported by a thrust bearing which includes, in the present exemplification, a sphere 36 having its surfaces in contact with concave recesses formed respectively in the end of the shaft 32 and in the end of a screw 37. The latter has its head extending below the thickened portion and may at this point conveniently mount a lock-nut 38. Consequently, it will be understood that by means of the screw 37 adjustment may be readily made which will prevent undue play on the part of the shaft 32 and will also permit of the latter being caused to assume any proper position. The connection between the brush head and this shaft preferably embraces a projecting portion or stud 39, which forms a part of the head, and a notch or slot which forms a part of the shaft. Consequently, while the head may readily be removed from or coupled with the shaft, these parts will normally rotate as a unit. With final reference to this portion of the mechanism, it will be observed that in order to prevent upward movement on the part of the applying roll or brush, the housing element 17 may be extended, as has been indicated at 40, and a pivot screw 41 may be mounted by this extended portion in axial alignment with the shaft 32. Thus, the head or applying roll, while free to rotate, cannot be accidentally displaced, but by simply lifting the housing 17 it is entirely practical to remove this member as a unit. Additionally, it will be noted that by this extended portion there is provided, in cooperation with the thickened portion 31, an encasing member which will act as a protecting guard for the applying roll.

With a view to providing a drive for this mechanism, it will be noted that the driven shaft 12, extending from the motor, carries a sprocket gear 42, which serves to drive a chain 43 passing around a sprocket 44. The latter is mounted upon a shaft 45, carrying a sprocket 46, in turn coupled through a chain 47 to a sprocket 48. This sprocket serves to rotate gears 49, 50, and 51, the former being secured to shaft 22 and the latter being coupled to shaft 39. The shaft 45 also carries a bevel gear 52 meshing with a similar gear 53 which, by means of a key or otherwise, is coupled to the shaft 32. Consequently, as the shaft 45 is driven, the shaft 32, together with the applying roll, will be rotated.

In conclusion, it will be noted that there is

preferably associated with the applying roll a wiper 54 which may be formed of fibre, and cooperates with the periphery and adjacent surfaces of the roll. While any desired form of mounting may be utilized, it is preferred that it be secured to a screw-threaded stem 55, with which a knurled nut 56 cooperates, and a spring 57 normally tends to project the wiper into contact with the surface of the roll.

Assuming that the parts are disposed in the manner before described, and that the reservoir is filled to a proper depth with cement or other desired fluid, it will be appreciated that, with the motor operating, both the wheels 21 and 29 will be rotated (in counter-clockwise directions). Surplus fluid will be removed from the wheel 21, due to the provision of the wiper 54, it being thus possible to accurately adjust the thickness of fluid film adhering to the surface of this roll or wheel. At their points of greatest proximity—and incident to the relatively minute spacing of the wheels—the fluid is transferred to the wheel 29, it being, of course, appreciated that the latter, in effect, has only its periphery coated, for the reason that no splash may be transmitted past the shield, and also incident to the fact that the wheels have only their peripheral portions in cooperative relationship. The thin film of liquid is carried to the applying roll or brush, and the latter is revolved so as to receive an even coating of fluid and to distribute the same at a point at which the operator may bring surfaces to be coated in contact with the same. Again, before this point is reached, the thickness of fluid film upon the brush may be adjusted incident to the provision of wiper 54, and it will thus be appreciated that, in this manner, it is possible to accurately adjust the parts so that the desired amount of cement or other fluid is delivered.

Of course, in lieu of the various drives which have been illustrated, any desired form of impelling mechanism might be substituted, but it will be noted that, regardless of this mechanism, a construction is provided which permits of instantaneous accessibility to all parts. Due to the fact that the shafts 22 and 30 are preferably vertically off-set, and also due to the fact that the body of the applying roll or brush extends normally at an angle of approximately thirty degrees to the horizontal, the operator may at all times secure a clear view of his work and thus perform his task with maximum efficiency. If, however, for any desired reason, it is necessary to change this angle, this may readily be achieved by simply loosening the bolt 9 or its equivalent and inclining the housing as may be desired, within practical limits.

Thus, among others, the several objects of the invention as specifically afore noted are achieved. It will be understood that numerous changes in construction and rearrangements of the parts might be resorted to, without departing from the spirit of the invention as defined by the claims.

The invention having thus been fully described, what is claimed as new and desired to be protected by Letters-Patent is:

1. A shoe bottom cementing machine including, in combination, a casing providing a fluid reservoir, a roll having a peripheral applying surface against which a shoe bottom is to be urged by hand, said surface being engageable against the overturned lasting allowance but not against the side of the upper of a lasted shoe, said roll being mounted with said work contacting surface

in an inclined position so that the overturned lasting allowance of a shoe held thereagainst may be viewed from above, the lower peripheral portion of said roll extending through an opening in said casing and beyond the same, means for transmitting from said reservoir to said member a quantity of reservoir fluid, and means for driving said roll.

2. A shoe bottom cementing machine comprising, in combination, a cement reservoir, a pair of rotary members disposed one above the other, means for mounting said members to have portions moving in predeterminedly spaced proximity to each other, the lower part of the lowermost 15 of such members being immersed in the cement of said reservoir, said lowermost member transferring such substance to said spaced uppermost member adjacent said point of proximity, an applying member movable adjacent the uppermost 20 of said rotary members and adapted to receive cement therefrom, means for driving said predeterminedly spaced members in the same direction and for driving said applying member, and means cooperating with the lowermost of 25 said rotary members and with said applying member for regulating, in each instance, the amount of cement transmitted by each of said members.

3. An applying machine for pyroxylin cement including a pair of rotary members disposed one above the other, means for mounting said members to have portions moving in proximity to each other, means for delivering the cement to be applied to the lowermost of such members, said lowermost member transferring such cement 35 to said uppermost member adjacent said point of proximity, an applying member movable adjacent the uppermost of said rotary members and adapted to receive material therefrom, means for driving all of said members, a shield substantially isolating the upper of said rotary members from the lowermost of the same, and means 40 mounted by said shield and cooperating with one of said members for controlling the amount of substance transmitted thereby.

4. An applying machine for pyroxylin cement including a pair of rotary members disposed one above the other, means for mounting said members to have portions moving in proximity to each other, means for delivering the cement to be applied to the lowermost of such members, said lowermost member transferring such cement 50 to said uppermost member adjacent said point of proximity, an applying member movable adjacent the uppermost of said rotary members and adapted to receive material therefrom, means for driving all of said members, and a shield extending between and substantially isolating the uppermost of said rotary members from the lowermost of the same.

5. An applying machine including a pair of rotary members disposed one above the other, means for mounting said members to have portions moving in predeterminedly spaced proximity to each other, means for delivering a substance 65 to be applied to the lowermost of such members, said lowermost member transferring such substance to said uppermost member adjacent said point of proximity, an applying member movable adjacent the uppermost of said rotary members and adapted to receive material therefrom, means for driving said rotary members in the same direction and at substantially the same peripheral speed, means for rotating said applying member, a shield extending between and substantially isolating the uppermost of said rotary

members from the lowermost of the same, and means mounted by said shield and cooperating with the lowermost of said rotary members for controlling the amount of substance transmitted thereby.

6. A shoe bottom cementing machine comprising, in combination, a casing providing a cement reservoir, a roll having a peripheral applying surface against which a shoe bottom may be urged by hand, said roll surface being engageable against the overturned lasting allowance but not against the sides of the upper of a lasted shoe and being located in a downwardly facing inclined position so that the overturned lasting allowance of a shoe held thereagainst may be viewed from above, means for transmitting cement from said reservoir to said roll, and means for driving said roll.

7. A shoe bottom cementing machine including, in combination, a casing providing a cement reservoir, a roll mounted in inclined position on a wall of said casing with its uppermost peripheral portion located interiorly and its lowermost peripheral portion located exteriorly of said casing, said lowermost peripheral portion being engageable against the overturned lasting allowance, but not against the sides of the upper, of a lasted shoe and being adapted to have work held thereagainst in position, to have its overturned lasting allowance viewed from above, means for transmitting fluid from said reservoir to said roll including a vertical wheel having its periphery in cement transferring relation with the interiorly located peripheral portion of said inclined roll, means for controlling the quantity of fluid transmitted to the applying surface of said roll, and driving means for said roll located therebeneath in position not to interfere with visual access to said work.

8. An applying machine including, in combination, a casing providing a fluid reservoir, a shaft rotatably mounted along a wall of said casing, an applying member detachably seated on the upper end of said shaft for rotation therewith, a cover for said casing, means on said cover for holding said member seated on said shaft when the cover is in closed position, said member having a fluid receiving portion located interiorly of said casing and a fluid applying portion located exteriorly of said casing, means in said casing for transmitting fluid from said reservoir to said fluid receiving portion, and means for driving said shaft.

9. An applying machine including in combination, a casing providing a fluid reservoir, said casing having an inclined sidewall thickened to provide a shaft bearing, an inclined shaft rotatably mounted in said bearing, an applying member detachably seated on said shaft for rotation therewith, a hinged cover for said casing overlying said member, means on said cover for holding said member seated on said shaft when the cover is in closed position, the uppermost peripheral portion of said member being located interiorly of said casing and the lowermost peripheral portion thereof being located exteriorly of said casing to provide a surface against which work may be held, means in said casing for transmitting fluid from said reservoir to said member including a fluid transfer wheel having its periphery in fluid transferring relation with the interiorly located portion of said member, and means for driving said shaft and said fluid transmitting means.

10. A shoe bottom cementing machine includ-

- 5 ing in combination, a casing providing a cement reservoir, a roll mounted in inclined position on a wall of said casing with its uppermost peripheral portion located interiorly and its lowermost peripheral portion located exteriorly of said casing, said lowermost peripheral portion being engageable against the overturned lasting allowance but not against the sides of the upper of a lasted shoe and being adapted to have work

held thereagainst in position to have its overturned lasting allowance view from above, means for transmitting fluid from said reservoir to said roll including a wheel in cement transferring relation with the interiorly located portion of said inclined roll, and driving means for said roll located therebeneath in position not to interfere with visual access to said work.

5 WILLIAM C. CARD, JR.
